UNITED STATES PATENT OFFICE

HOMER W. JONES AND RALPH R. SMITH, OF JACKSON HEIGHTS, NEW YORK, ASSIGNEES
TO NATIONAL CARBON COMPANY, INC., A CORPORATION OF NEW YORK

ELECTRIC SIGNAL LAMP

Application filed November 11, 1925. Serial No. 68,413.

This invention relates to electrical signal devices, and more particularly to a unitary battery hand lamp adapted to be used for signalling purposes, as by the police for regulating traffic at night.

The primary object of the present invention is to provide a simple unitary illuminated signal device adapted to be conveniently carried in the palm of either hand of the operator and to be easily operated by his thumb.

A further object of the invention is to provide a novel case and mounting for the several parts of the lamp to render them easily accessible, and to provide a novel hook and band construction on the case to hold the latter in its proper position on the operator's hand.

Other features and advantages of the invention will be made clear by a description of a preferred embodiment thereof as illustrated in the accompanying drawings, in which:

Fig. 1 is a top plan view of an embodiment of the present invention;

Fig. 2 is a sectional view of Fig. 1 taken on the line 2—2 looking in the direction of the arrows;

Fig. 3 is a rear view of the signal device;

Figs. 4, 5 and 6 are, respectively, views of the front, top and bottom of the cell-supporting frame and the case section carrying it.

Broadly speaking, a hand signal device embodying the present invention comprises a battery case adapted to be carried in and secured to an operator's hand by suitable attaching means M on one side of the case. The opposite side of the case carries a lamp L and a switch S is disposed on the upper edge of the case so that the operator may close the lamp-and-battery circuit by operating the switch with his thumb when he wishes to flash the lamp.

Referring to the drawings, a case A adapted to carry all the parts of the hand signal device may consist of complementary front and rear sections 10, 11 joined together permanently along one edge by a hinge 12 and locked at the other edges by a depressible

catch 13. The front 10 is pressed out as at 10' to provide a boss forming a chamber 14, and is apertured as at 10'' to receive a bulb socket 15 threaded to fit the electric light bulb L. The forward end of the socket 15 is soldered or otherwise secured to an inturned flange of the boss 10', whereby the threaded portion of the bulb socket and the bulb therein are in electrical connection with the casing.

The front and rear casing sections are also provided with complementary semi-circular recesses in their upper edges to provide a circular opening to receive the shell 17 that carries the switch S, said shell being soldered or otherwise secured in the recess in the front section and projecting into the casing.

The switch S may consist of a depressible button 18 forming an enlarged head on a stem 19 that has a washer 20 secured to its lower end, as by a reduced part 21 on the stem that projects

through the washer and is riveted over. A spring 22 bears against the inside bottom of the shell 17 and against the under side of the button 18 to restore the latter to normal position after it has been depressed, and the stem 19 projects through and is guided by an apertured neck 23 in the bottom of the shell.

The washer 20 is carried by the stem outside the shell and is of larger diameter than the aperture in the neck 23 so that the washer limits

the outward movement of the push-button.

The push-button is operable to connect the lamp L in circuit with the battery through a conductor D which is secured to the inside of the front section 10 by a rivet 25 but insulated

therefrom by suitable insulation 26. One resilient arm 27 of the conductor projects opposite the lamp socket 15 to be engageable by the center lamp contact, while the other

resilient arm 28 projects beneath the end of the stem to be depressed by the latter into contact with the spring cell terminal or contact 29 secured to the frame F that carries the battery cells. The side of the arm 28 adjacent the switch stem is covered by an extension of the strip 26 to insulate it from said stem.

The cell-supporting frame F is mounted on the inside wall of the rear casing section 11 and may be of any suitable design to carry

two dry cells side by side in series circuit with one another, with one pole of the series-connected cells electrically connected to the casing and the other pole electrically connected to the terminal contact 29. As shown, the frame F comprises a U-shape bracket 30 secured thereto but insulated therefrom and having upper and lower limbs 31, 32, the limb 31 comprising an arm 33 having the terminal 29 secured thereto but insulated therefrom. The other arm 34 of the limb 31 is spaced from the arm 33, and the contact 29 projects opposite the space between said arms so as to be engageable by the depressible arm 28 that projects opposite said space perpendicular to the contact 29. The lower limb 32 provides a bearing for a member 35 that has two resilient arms 36 and 37, the arm 36 being electrically in circuit with the cell thereon and the arm 37 being insulated from the cell which it supports. The container electrode of the latter cell may be connected directly to the casing by a conductor strip 39. The secured end of the contact 29 is engageable by the center carbon pole of the cell which has its zinc container electrode disposed on the arm 36, and the arm 36 is electrically in circuit with the arm 34 that is engageable by the center pole of the cell that rests on the arm 37, whereby the cells are electrically connected in series through the U-shape member 30. The cells are individually removable and replaceable, and by closing the sections 10, 11 together the arm 28 is moved into place above the contact 29 so that the lamp may be flashed by depressing the button 18.

In order to secure the casing to the hand of an operator, attaching means M are provided on the rear of said casing. The said means comprises a band 40, preferably of elastic material, fastened at one end to a hook 41, and at the lower end to a plate 42. Another slotted plate 43 is provided to receive the hook 41. The plates 42, 43 may be secured to the outside of the case section 11 by the rivets 44 which secure the frame F to the inside of said section.

The operation of the improved signal device is self evident from the foregoing description and the drawings. By inserting four fingers of either hand between the casing and the elastic band 40, the thumb of the hand holding the device is in position to operate the push-button. The device is desirably placed in front of the palm of the hand, where it is held firmly in place by the band, but for some purposes it may also be used on the back of the hand. The button operating the control switch located on the top of the casing is easily actuated by a slight pressure from the operator's thumb. When the switch is depressed the end of the stem 19 engages the end of the conductor 28 and forces it against contact 29 to complete the electrical circuit

from the cells to the lamp. It will be observed that the switch and lamp are substantially within the outline of the casing to avoid damaging them.

While a preferred construction is illustrated and described, it is to be understood that variations may be made without departing from the scope and spirit of the invention.

We claim:

1. A battery hand lamp comprising the combination of a hinged two-part casing, a lamp mounted on the front wall of one part of said casing, a conductor secured to said front wall having a part disposed to be engaged by said lamp and a part extending opposite the upper wall of said casing, cell supporting means mounted on the other part of said casing and having a terminal, and a switch operable to electrically connect said terminal and last-mentioned part of said conductor. 75

2. A battery hand lamp comprising the combination composed of complementary hinged members, a lamp mounted on the front wall of one member of said casing, a conductor secured to said front wall having a part engageable by the center contact of said lamp and a part extending inwardly opposite the top wall of said casing, cell 90 supporting means mounted on the other member of said casing and having a terminal, and a switch disposed within the outline of the top of said casing and operable to depress the last-mentioned part of said conductor into contact with said cell terminal. 95

3. A battery hand lamp comprising the combination of a casing, means on the rear wall thereof for securing it to a support, cell supporting means carried by said wall and having a terminal, a lamp mounted on the front wall of said casing, a conductor having a part engageable by the center contact of said lamp and a part disposed adjacent said terminal, and a switch operable to deflect the last-named part of said conductor to electrically connect the same and said terminal. 105

4. A battery hand lamp comprising the combination of a casing consisting of front and rear complementary sections provided with recesses in corresponding opposed edges to form an opening for a switch, cell supporting means carried in the rear casing section and having a terminal disposed opposite said opening, a lamp mounted on the front section, a conductor having a part engaging the center contact of said lamp and a part disposed opposite said opening, and a switch disposed in said opening and operable to electrically connect said terminal and the last-mentioned part of said conductor. 115

5. A battery hand lamp as claimed in claim 4, in which said sections are hinged to one another, said conductor is secured inside said 120

front section, and said switch comprises a housing secured in one of said recesses and projecting within said casing.

6. A battery hand lamp as claimed in claim 4, in which said sections are hinged together and the recesses are in the upper walls of the sections, said cell-supporting means comprises a frame arranged to support two cells side by side, said conductor is secured inside said front section above said lamp, and said switch comprises a housing secured in one of said recesses and projecting into said casing and includes a depressible member adapted to move said conductor part against said terminal, which latter is secured to said cell-supporting frame.

In testimony whereof, we affix our signatures.

HOMER W. JONES.
RALPH R. SMITH.
